UNITED STATES PATENT OFFICE.

HARRY CLINE, OF IDAVILLE, PENNSYLVANIA.

PUMP.

No. 856,845.

Specification of Letters Patent.

Patented June 11, 1907.

Application filed August 4, 1906. Serial No. 329,263.

To all whom it may concern:

Be it known that I, HARRY CLINE, a citizen of the United States, residing at Idaville, in the county of Adams and State of Pennsylvania, have invented new and useful Improvements in Pumps, of which the following is a specification.

This invention relates to pumps of the type known as double-acting force pumps embodying a cylinder and a reciprocating piston, and has for its objects to provide a comparatively simple, inexpensive device of this character wherein the water will be lifted both upon the upward and downward stroke of the piston, and one wherein the water will be forced in a continuous stream upward through the stand-pipe.

With these and other objects in view, the invention comprises the novel features of construction and combination of parts more fully hereinafter described.

In the accompanying drawings: Figure 1 is a vertical section, taken centrally and longitudinally through a pump embodying the invention and showing the piston in its upward position or stroke. Fig. 2 is a similar view showing the piston on its down stroke.

Referring to the drawings, 1 designates the pump barrel or cylinder connected at its upper end upon and for communication with the lower end of a stand-pipe 2, there being provided at the lower end of the cylinder an inlet port 3 adapted for communication with the lower end of an intake pipe 4 disposed centrally in and extended partially through the cylinder 1, while fixed upon the upper, open end of the pipe 4, which is provided adjacent its upper end with an annular series of openings or passages 5, is a head 6 having a marginal groove in which is arranged a rubber or other packing gasket 7.

Mounted for reciprocation in the cylinder 1 is a duplex pumping piston comprising a cylindrical tubular body portion 8, in which the head 6 fits, and end heads 9 and 10 provided respectively with openings or ports 11, 12, and of which the head 9 is engaged with the lower end of a pumping rod 13 extended upward through the stand-pipe 2, while the head 10 is provided with a tubular neck 14 formed to fit and slide upon the intake pipe 4, there being mounted on the rod 13, which is provided with a stop or abutment 15, a movable valve 16 adapted for closing the ports 11, a similar valve 17 adapted for closing the

ports 12 being movably mounted on the neck 14 onto the outer or lower end of which there is tapped a nut 18 constituting a stop for limiting the opening movement of the valve. 60

Arranged above the head 6 for closing the upper open end of the intake pipe 4 is a valve 19 connected by members or bolts 20 extended through suitable openings in the head with a valve 21 arranged to slide on the pipe 65 4 and for closing the openings 5, it being understood, of course, that the connecting members 20 are susceptible of sliding movement in the openings in the head to permit of alternate movement of the valves 19 and 21 to open or closed position.

In practice, during reciprocation of the piston 8 and upon its outstroke the valve 16 will close the ports 11 and the valve 17 move to open position, while at the same time the 75 valve 19 will move to open position and valve 21 to position for closing the passages 5 whereby water will be drawn upward through the intake pipe 4 and delivered into the upper portion of the cylinder 8 above the head 80 6, while at the same time the water previously delivered into the lower portion of the piston body 8 below the head 6 will be forced outward through the ports 12 into the pump cylinder 1. On down stroke of the 85 pumping piston the valve 17 will move to closed position and the valve 16 to open position, while at the same time the valve 19 will close and valve 21 open, whereby the water will be drawn upward through the intake 90 pipe 4 and pass through the openings 5 into the lower portion of the piston body 8 below the head 6, the water in the upper portion of the piston body being at the same time discharged through the openings 11 into the 95 pump cylinder 1. During either stroke of the pumping piston water in the cylinder 1 will be forced upward through the stand-pipe 2, thus insuring the delivery of the water in a continuous stream through said pipe to the 100 pump.

Having thus described my invention, what I claim is:

In a pump, a barrel, a stand-pipe communicating therewith, an open ended intake pipe 105 sustained in and extending partly through the barrel, a pumping piston arranged for reciprocation in the barrel and comprising a tubular body portion having end heads provided with ports, a head fixed on the intake 110 pipe and fitted within the tubular body portion of the piston, the intake pipe being pro-

vided with transverse ports at a point adjacent the head, movable valves sustained for alternately closing the ports in the heads of the pumping piston during reciprocation of the latter, valves disposed at opposite sides of the fixed head for closing respectively the inner end of the intake pipe and the trans-
verse ports therein, and connecting members slidably mounted in the fixed head and con-

necting the last named valves for alternate movement to open or closed position.

In testimony whereof, I affix my signature in presence of two witnesses.

HARRY CLINE.
